UNITED STATES PATENT OFFICE.

BENJAMIN F. ARMSTRONG, OF CLEVELAND, OHIO.

ATTACHMENT FOR CAN COVERS.

Application filed May 10, 1922. Serial No. 559,963.

To all whom it may concern:

Be it known that I, BENJAMIN F. ARMSTRONG, a citizen of the United States, residing at Cleveland, in the county of Cuyahoga and State of Ohio, have invented certain new and useful Improvements in an Attachment for Can Covers, of which the following is a specification.

My object is to provide an efficient and inexpensive spring device for holding loose printed matter or a booklet within a dished cover of a can or other tin container storing paint, syrup, preserves, or any liquid or hard material. The device is also particularly designed and constructed to be easily attached and detached from a cover fixed in place in the can, or to be removed with the cover without displacement or release of the printed matter within the cover. Thus, a printed folder or booklet may be securely fastened in place within the cover when the latter functions to seal the can, but nevertheless accessible to permit such folder or booklet to be removed and opened; and when the cover is released and detached from the can this folder or booklet may be deposited and locked within the cover and the interlocked parts handled as a unit although readily separable if occasion requires.

In the annexed drawing, Fig. 1 is a perspective view of a sealed tin can having my improved spring holder attached to the cover, and Fig. 2 is a side view, partly in section, of a can and its cover and my spring holder and showing a thumb and forefinger in the act of releasing the holder. Fig. 3 is a perspective of the can cover and its spring holder attached together and holding printed matter in the dished side of the cover. Fig. 4 is a sectional view of the cover and printed matter and a side view of the spring holder locked together as a portable unit. Fig. 5 is a perspective unit. Fig. 6 is a perspective view of a printed folder or booklet, and Fig. 7 is a perspective view of a modified form of spring holder.

As shown the invention is applied to a paint can 2 having a depressed top 3 possessing a large central opening which is bordered by a friction flange 4 extending downwardly from a raised edge or seat 5 for a removable cover 6. The body of this cover is dished deeply and has inclined sides 7 to frictionally engage depending flange 4, and a horizontal flange 8 on the cover extends

outwardly to a substantial distance beyond raised edge 5, thereby leaving a space between this flange 8 and the inclined offset portion 9 of top 3, see Fig. 2. Thus, the cover may be pressed tightly to its limit in the opening of the can top and still leave a gap or space beneath the overlapping flange 8, which may have its peripheral edge beaded or doubled back upon itself to provide a round smooth edge.

In many instances it is desirable to furnish printed directions, formulas, recipes, or pertinent advertising matter relating to the contents or mixtures contained in the can. Such printed matter is often necessary to permit the goods to be properly prepared, mixed or used, and where the contents of the can are drawn upon repeatedly it is desirable that the printed matter be preserved or kept for repeated reference. To protect this printed matter from the contents when the can is opened, and to prevent the printed matter being lost but at the same time accessible for immediate reference, I have conceived the idea of using a snap locking member or spring holder 11 to secure the printed matter, such as a folder or booklet 12, within the concaved or dished side of the cover, and to attach this member to the cover so that it may be affixed thereto and removed therefrom at will either when the cover is pressed into the can or when said cover is removed and laid aside. To that end, spring holder 11 is made of a relatively thin strip of spring metal bent upwardly at its opposite ends and thence outwardly and finally turned downwardly and inwardly to provide short hooks 14 at both extremities. The vertical portions 15 of this spring strip place the main connecting portion 16 thereof in a relatively lower horizontal plane than the hook extremities 14; thereby permitting middle portion 16 to function as an elongated pressure bar adapted to hold either a thin or thick folder or booklet 12 firmly within the dished cover when the hooked extremities 14 are engaged with the opposite edges of flange 8 of the cover. To provide additional flexibility and an accommodating surrender in this spring holder at opposite ends thereof I prefer to incline the short vertical portions in respect to the horizontal middle portion of the bar, thereby making it possible to accommodate folders or booklets of different thicknesses and to permit effective interlocking and an

attachable and detachable connection with the edges of the cover.

To further promote locking engagement and unlocking of the hooked extremities with flange 8 I prefer to incline the portions 15 of the spring locking bar inwardly toward each other, thereby localizing the spring action so that the hooked extremities may be moved outwardly a substantial distance 10 horizontally and so that a decided contraction will take place at each end of this spring holder when the finger pressure is relieved. The Z or S formation of the ends of the spring holder also provide prominent and 15 accessible finger holds as plainly shown in Fig. 2. In Fig. 7, the vertical portions 15' are inclined outwardly and one of the hooked extremities has a downwardly slanting end 17 to permit a snap engagement with 20 the edge of the cover.

When the cover is in sealing position within the top of the can and the locking member is also in place on the cover the device and the top edges of the can are substantially 25 flush. Therefore, similarly equipped cans may be piled or stacked upon each other without interference and without accidentally dislodging or releasing the spring holders. These friction covers are also automatically applied and pressed to their seats 30 by means of machines called capping machines, and the spring holders and matter held thereby may be attached to the covers before the covers are operated upon by 35 these machines and without affecting the operations of such machines. Or the printed matter or other article may be placed within the cover and locked in place by the locking member after the covers have been 40 affixed to the cans.

What I claim, is:

1. An attachment for a can having a dished cover comprising a spring member detachably engaged in spring connection at

its ends with the opposite edges of the cover 45 and projected downwardly intermediate said ends into the dished side of the cover and adapted to secure solid matter removably within said cover whether the latter is affixed to or separated from the can. 50

2. An attachment for a can having a dished cover provided with a border flange, comprising a spring holder having hooked extremities adapted to engage said flange and to spring outwardly to be readily disconnected and bent downwardly at its 55 middle portion to engage and hold solid matter deposited within the dished side of the cover.

3. An attachment for a friction can 60 cover having a circumferential flange and a central depression, comprising a thin strip of metal having hooked extremities and short vertical spring portions adjacent said extremities adapted to promote interlocking 65 with said flange and spaced apart therefrom to permit said hooked extremities to be pressed outwardly.

4. An attachment for a dished friction 70 can cover having a laterally extending circumferential flange, comprising a strip of spring metal having a straight middle portion bent upwardly at an inclination at opposite ends thereof and terminating in hook 75 portions adapted to engage said flange, the straight middle portion of said strip being adapted to extend into the dished side of said cover to hold solid matter deposited therein.

5. A can, cover having a dished central 80 portion and a circumferential flange, in combination with a straight strip of spring metal holding loose matter within said dished portion having Z shaped end portions terminating in hooks adapted to detachably 85 interlock with said flange.

In testimony whereof I affix my signature.
BENJAMIN F. ARMSTRONG.
